Primary Examiner — Paula Allen Greene(74) *Attorney, Agent, or Firm* — Haynes and Boone, LLP(57) **CLAIM**

The ornamental design for an earpiece, as shown and described.

DESCRIPTION

FIG. 1 is a front right perspective view of an earpiece showing our new design;

FIG. 2 is a rear left perspective view thereof;

FIG. 3 is a left side elevational view thereof;

FIG. 4 is a right side elevational view thereof;

FIG. 5 is a front side elevational view thereof;

FIG. 6 is a rear side elevational view thereof;

FIG. 7 is a top plan view thereof; and,

FIG. 8 is a bottom plan view thereof.

FIG. 9 is a front right perspective view of the earpiece engaged with an example audio device; and,

FIG. 10 is a rear right perspective view thereof.

The broken lines in the drawings illustrate environmental features and form no part of the claimed design.

1 Claim, 10 Drawing Sheets# US D839,243 S
